UNITED STATES PATENT OFFICE.

ALANSON P. BRUSH, OF DETROIT, MICHIGAN.

MUFFLER.

SPECIFICATION forming part of Letters Patent No. 784,833, dated March 14, 1905.

Application filed December 6, 1904. Serial No. 235,708.

To all whom it may concern:

Be it known that I, ALANSON P. BRUSH, a citizen of the United States, residing at Detroit, county of Wayne, State of Michigan, have invented a certain new and useful Improvement in Mufflers, of which the following is a specification, reference being had to the accompanying drawings, which form a part of this specification.

My invention is designed to provide a novel muffler, the same being more particularly adapted for use as a muffler for the products of combustion in an internal-combustion engine, although my invention contemplates its use wherever it may be found adapted.

My invention consists of the structure hereinafter described and claimed, and illustrated in the accompanying drawings, in which—

Figure 1 is a view in section, showing parts in plan or elevation, as the case may be. Fig. 2 is a view of parts in section, showing a modification. Fig. 3 is a view in cross-section on the line 3 3, Fig. 2.

In the drawings, *a* represents an exhaust pipe or channel to carry the products of combustion from the combustion-chamber of the cylinder of an internal-combustion engine. The extremity of the exhaust-pipe is led into a coincident pipe or channel, (indicated at *b*.) Both the pipes *a* and *b* communicate with a muffler drum or chamber (indicated at *c*) of any suitable proportions. Leading from the pipe or channel *b* toward its base is a conductor *d*. This conductor *d* I have shown communicating with the interior of a pipe or channel *e*, from which leads a coincident pipe *f*. Both the pipes *e* and *f* communicate with a second or additional muffler-drum *g*. To the opposite end of the discharge-pipe *f* is connected a discharge-pipe *h*, (shown in the drawings submitted herewith,) communicating with the atmosphere at its outer end. The chambers *c* and *g* may be of any suitable construction. As shown, they are each formed with heads *i* and *j* at opposite extremities and a suitable cylinder *k*, secured to said heads, the heads being shown connecting by connecting-rods *l*; but I do not limit myself to any specific construction of said chambers.

I have shown herewith two chambers, the

one communicating into the other through the conductor *d*, and I have shown means whereby the second drum or chamber, as the drum *g*, discharges to the atmosphere. I do not, however, limit myself to the employment of two muffler-chambers, inasmuch as for some purposes a single chamber with its connected parts may be found sufficient, and in other cases it will readily be seen that the discharge-pipe *h* might lead into an additional muffler-drum constructed and arranged with parts corresponding to the drum *c*. My invention therefore contemplates as coming within its scope the employment of either a single muffler-drum or chamber with its connecting parts or any desired multiple of drums connected up in a manner similar to that illustrated in the accompanying drawings. For many purposes, however, the employment of two muffler-drums, the one discharging into the other, will be found sufficient. The case of each of the drums with the corresponding heads are made tight, and it will be perceived that there are no small orifices employed to be stopped up with soot. It will also be perceived when the products of combustion are discharged from the exhaust-pipe *a* into the drum *c* there is no appreciable back pressure. The gases discharged into the muffler-drum, it will readily be perceived, do not pass through the muffler-drum at all, but simply enter one end thereof, the gases being turned back to find their exit through the coincident opening within the channel *b*, (shown in Fig. 1,) located about the inner end of the exhaust-pipe. The gases passing into the muffler-drum retard in some degree the discharge of the gases from the muffler, the elasticity of the gases in the drum taking the shock of the entering discharge, the gas in the drum being slightly compressed by the momentum of the incoming gases. It is obvious that the gas will leave the first drum *c* in a long impulse instead of in short and sharp impulses, like the impulses of the incoming charge or exhaust. The gases will flow out thus from the first drum at a slow rate of speed and in prolonged impulses. It will be understood that the exhaust passes through the pipe *a* in a series of short and

sudden impulses, and because of the retarding effect already described the outward flow from the drum will be, as above stated, in longer impulses. The exhaust-gases passing 5 through the connecting-pipe *d* enter the next drum, where practically the same process is repeated as already described as taking place in the first drum, the impulses after leaving the first drum being longer and slower than 10 the entering impulses of the exhaust. The gases will not flow into the second drum so but that they can readily be handled through pipes of smaller area. Consequently the coincident openings into and from the second 15 drum may be reduced. The process may thus be carried on until the flow from the drums will become a steady and continuous flow without any trace of impulses whatever. The last discharge would need to be one of sufficient area to handle the quantity of gas to 20 flow therefrom in a steady continuous flow or a flow that was perfectly uniform. In practice it is found that two chambers of sufficient capacity will give a close approximation 25 to a continuous flow of the exhaust to the atmosphere. If it was desired, the openings into and from the chambers might be reduced, so as to increase the velocity of the gas, and thereby increase the compression in 30 the corresponding chamber. While this would begin to cause a back pressure, still we might use but a single chamber with very fair results. Because the inlets and outlets are practically coincident the gases do not materially 35 change in the drum—*i. e.*, in use the drums will each become gradually filled with the exhaust-gases—and if a motor fail to explode or the electric current should be cut off the motor would force a few charges of explosive 40 mixture into the muffling system; but the charges would not pass through the drums and would not take the place of the non-explosive gases in the drums, but the charge would go out of the one drum and into and out of the 45 other to the atmosphere in a manner already set forth.

In Fig. 1 the pipes *a b* and *c f* are shown concentric, and the pipes may be so arranged—that is, practically concentric, it being unnecessary that they should be thus arranged with exactness.

In Figs. 2 and 3 the pipes are coincident at their extremities within the adjacent end of the corresponding drum; but, as indicated 55 more particularly in Fig. 3, the said pipes or channels may be elongated at their inner ends. In Fig. 1 the pipes *b e* are arranged about the pipes *a f*, respectively.

In Figs. 2 and 3 the openings of the pipes 60 are arranged side by side; but in either way the openings of said pipes are coincident. It will also be obvious that the pipes *b e*, through which the muffler-chambers discharge, are longer than the corresponding pipes *a f*, the 65 pipes *b e* thus each forming practically, on ac-

count of their extension beyond the extremities of the pipes *a f*, a single inlet and outlet opening. It will be evident that a muffler so constructed is of superior efficiency and utility, inasmuch as each of the mufflers is without 70 back pressure and the mechanism is without small apertures or complications of construction of any kind, and inasmuch, also, as with this construction there cannot occur explosions of unburned charges within the muffler-chambers, with the attendant unpleasantness and danger of destruction. 75

It will be obvious that owing to the arrangement of the coincident openings of the inflow and outflow discharges a siphoning effect results, whereby the outflow of gas is retarded. 80

What I claim as my invention is—

1. A muffler comprising multiple chambers, an exhaust-pipe leading into one end of one of the chambers, an exhaust-pipe leading from 85 the same end of said chamber into one end of a second chamber, and an exhaust-pipe leading from the same end of the second chamber as set forth.

2. A muffler comprising multiple chambers 90 each provided at one end thereof with an outflow-channel communicating therewith, a pipe connecting said channels, an exhaust-pipe leading into one of said channels, and an exhaust-pipe leading from the other of said channels. 95

3. A muffler comprising a muffler-chamber having inlet and outlet passages coincident the one with the other, the outlet-passage projecting within the chamber beyond the inlet-passage. 100

4. A muffler comprising a muffler-chamber having inlet and outlet passages coincident the one with the other, the outlet-passage leading into the chamber beyond the opening of the inlet-passage whereby the outflow of the gases 105 will be retarded by the inflow.

5. A muffler comprising a muffler-chamber having inlet and outlet passages coincident the one with the other, said passages arranged to form a single opening at the extremity of the 110 outlet-passage within said chamber.

6. A muffler comprising plural communicating muffler-chambers connected in series substantially as set forth, an exhaust-channel leading into one end of one of said chambers, and an exhaust-channel leading from the corresponding end of the other of said chambers. 115

7. A muffler comprising plural communicating muffler-chambers, each of said chambers provided with coincident inlet and outlet openings, said openings arranged so that the inflow of gas through the inlet-channel will retard the outflow of gas through the outlet-channel. 120

In testimony whereof I have signed this specification in the presence of two subscribing 125 witnesses.

ALANSON P. BRUSH.
